UNITED STATES PATENT OFFICE.

ARTHUR QUENZER, OF BROOKLYN, NEW YORK.

ANKLE-SUPPORTER.

No. 921,563.

Specification of Letters Patent.

Patented May 11, 1909.

Application filed January 9, 1908. Serial No. 409,978.

To all whom it may concern:

Be it known that I, ARTHUR QUENZER, a citizen of the United States, residing at Brooklyn, in the State of New York, have 5 invented certain new and useful Improvements in Ankle-Supporters, of which the following is a specification.

My invention relates to bandages which may be used to support an injured limb and 10 is more particularly intended as an ankle supporter which may be used in case of a sprain or other injury thereto.

The object of this invention is to provide 15 a bandage which will furnish ample support for the injured part and yet will be sufficiently resilient to yield to the natural movements of the body.

My invention will be clearly understood 20 by referring to the accompanying drawings, in which—

Figure 1 is a perspective view of my ankle 25 supporter in position upon the foot and ankle of the wearer; Fig. 2 is a similar view with the upper or rear portion of the sup- porter unlaced.

Protectors for the joints of the arms or legs 30 have heretofore been constructed of elastic knitted fabric material, but in so far as I am aware they have not been provided with one 35 portion in tubular form and another portion fastened thereto and provided with a lacing so as to adapt them to different shapes and sizes of limbs and also enable the movement or pressure upon the injured part to be 40 changed to suit the condition of the injured member.

My improved ankle-supporter shown in 45 Figs. 1 and 2 comprises a front tubular portion A which is preferably made of elastic knitted fabric, which may be made of a single integral piece, or of different pieces fastened together. The fabric has its body portion formed with longitudinally-extending warp-threads, and also with top and bottom borders a, a, woven similarly to the body-piece but somewhat closer or of threads a uniform distance apart, so as to give a tighter hold on the foot at these points. The rear or upper portion B is likewise composed 50 of elastic woven fabric similarly provided with top and bottom borders b. This rear piece is divided longitudinally and is provided on either side with a non-yielding flexible material, composed of outer and inner strips C, C', preferably leather. These

border strips C may be made of a single thickness or of two thicknesses of material and closing the edges of the elastic fabric and secured thereto by stitching or in any other suitable manner. In the outer border 60 strip are placed a number of eyelets E, or hooks or other suitable fastenings, through which a lacing cord D may be passed to secure the supporter about the ankle after the front portion A has been drawn over the 65 instep of the foot as shown in the drawings. A flap or tongue F is fastened to one of the strips C and overlaps the meeting edges of the border strips C under the lacing cords and protects the limb of the wearer from 70 irritation or injury which might result from the pressure of the lacing thereon. The inner border piece also protects the wearer from contact or pressure of the eyelets E.

The front and rear portions of the sup- 75 porter are fastened together in any suitable manner at one or more points G on either side of the supporter, the parts being separated along other contiguous edges for the purpose of allowing the heel of the wearer 80 to protrude between the front and rear por- tions.

In case it is necessary to form a more rigid support for the instep, I may use a 85 form or mold of wood, rubber, metal or other material, placing the same in the front portion A and, if necessary, fastening by means of stitching or otherwise, so that it will be held up against the foot and form a support for the instep.

It will be observed that I have provided 90 an ankle supporter which will be sufficiently yielding to the movements of the bones and muscles of the ankle and foot and yet will furnish a sufficient binding to support the 95 injured member. The forward portion A will accurately conform to the shape of the instep and yet will not produce an undue binding or pressure of the delicate parts thereof inasmuch as there are no lacing de- 100 vices in this portion and will not be liable to form into folds or wrinkles and consequently irritation of the parts is entirely prevented.

By means of the lacing on the upper or 105 rear portion, the ankle may be bound with greater or less pressure, depending upon the condition of the injured member and yet will yield sufficiently to every movement of the ankle joint.

While I have shown the lacing as applied to the front of the supporter, it is obvious that I may apply the lacing at the side or other portions thereof.

5 The inner border strips C' and the tongue F thoroughly protect the ankle and limb of the wearer from injury or irritation of the eyelets and lacing cord.

10 While I have described my improved bandage as applied to the ankle, it may be found useful to bind and support other portions of the body.

Having now described my invention, what I claim and desire to secure by Letters Patent is—

15 1. A supporter comprising an integral tubular front portion and a rear portion divided and united by means of a lacing, said

front and rear portions being secured together at one or more points on each side of 20 the lacing.

2. A supporter comprising an integral tubular elastic portion and a divided or parted elastic portion having non-elastic edges provided with eyelets for a lacing and a 25 tongue-piece adapted to lap the edges when they are drawn together, said elastic portions being secured together on each side above the instep.

In testimony whereof I affix my signature, in presence of two witnesses.

ARTHUR QUENZER.
